HEATING BOILER

Elmer A. Hooper, Bridgeport, Conn., assignor to
 The McCathron Boiler Works Co., Inc., Bridge-
 port, Conn., a corporation of Connecticut

Application January 4, 1933. Serial No. 650,083

7 Claims. (Cl. 122—165)

This invention refers to improvements in water heaters or boilers especially adapted for the use of oil burners, which boilers are designed to be constructed of sheet steel, stay-bolted and electrically welded together.

An object of the invention is to provide a novel design of heater which can be constructed entirely of electrically welded sheet plate, and of a novel design whereby the intense and rapidly 10 travelling heat, as from the oil burner, is passed backward and forward through the heat passages five or more times so that when the smoke and other products of combustion enter the smoke flue, there will be a relatively small amount 15 of heat left in it.

A further object of the invention is to provide a sheet-steel type of boiler which primarily comprises an outer fixed water jacket that in part forms the main combustion chamber and 20 has a central opening therethrough, and to provide a removable water container of special construction that loosely fits into said central opening, and which has two elongated communicating heat passages one above the other, the lower 25 one having inlet passages and the upper one having outlet passages, all of which are surrounded by the water container in the jacket, and to include suitable pipe connections between the said outer water jacket and the inner water container, whereby a proper circulation of the water 30 is assured.

Further objects of the invention are to provide means for removably supporting the cylindrical jacket within the central opening of the 35 outer jacket and to enclose the same in said position with removable plates; also to provide suitable perforated baffle plates in the ends of the heat passages of the removable water jacket, and further to provide elongated plates against the 40 crown sheets of the outer water jacket to form suitable elongated heat passages intermediate of the outer water jacket and the inner removable water container to insure the travel of the heat to the best advantage between selected portions 45 of the two said water jackets.

While I have, in the accompanying drawings forming a part of this disclosure, illustrated two horizontal types of boilers, one including a single inner water container and the other provided 50 with two such containers, yet it will be understood that the heater may be modified to include three or more of these inner removable containers, thus forming what might be regarded as a battery of boilers in a single unit, both coming within the limitations of my invention.

The invention will therefore be more fully explained and readily understood by reference to the accompanying drawings showing preferred embodiments of the invention, and on which similar characters of reference will be found to indicate like or corresponding parts throughout the several figures, and of which

Fig. 1 shows a front elevation of my improved boiler having one closure plate removed;

Fig. 2 is a side elevation, as seen from the right 65 of Fig. 1;

Fig. 3 is a detached front elevation of one of the front closure plates, as used on both front and rear ends of the heater;

Fig. 4 shows an enlarged central vertical section 70 view, taken through the heater on line 4—4 of Fig. 1;

Fig. 5 shows a rear elevation, partly broken away, of the main outer water jacket of the heater, with closure plates and inner removable 75 water container detached;

Fig. 6 shows a rear end view of the inner water container removed from the outer water jacket shown in Fig. 5, and having one of the small 80 perforated baffle plates removed;

Fig. 7 is a side view of the baffle plate removed from the rear end of the inner removable water container, shown in Fig. 6;

Fig. 8 shows a vertical cross section through the inner removable water container, taken on 85 line 8—8 of Fig. 4, though on a smaller scale, as in Figs. 1 and 2; and

Fig. 9 shows a front elevation of a modified application of the invention, wherein a relatively larger outer water jacket is employed, and is 90 designed to accommodate two inner water containers instead of one, as illustrated in preceding views, the upper and lower portions of the outer water jacket and removable water container being provided with two outside detachable pipe connections to insure proper circulation of water through both water containers.

The heater may obviously be made in various sizes or lengths, since the differences in sizes of this particular make of boiler are largely determined by the length or depth from front to rear, the boiler shown in the drawings being relatively short, forming one of the smaller sizes, such for instance as would be adapted for residence purposes.

The boiler includes an outer water jacket 10 formed between the outer plate 11 and the inner or crown plate 12, which forms the two sides, top and end portions, of a combustion chamber 13 in the lower portion. A smoke outlet 14 is also 110

formed through the upper portion of the jacket, and an intermediate central elongated space is provided to accommodate the removable water container 15, later to be referred to. This outer 5 water jacket includes two aligned cylindrical openings 16, one in the front end and the other in the rear end of the heater, to freely and removably receive the said removable water container.

10 The legs of the outer water jacket may be supported on or lined with suitable brick work 17 and is provided with doors 18 and 19 through which the heater may be fired and cleaned, and to accommodate an oil burner 20 of any improved 15 type, the furnace, as before suggested, being more particularly designed for the use of oil, and to meet the requirements of sudden changes of temperature which are produced in furnaces when oil is used. The outer water jacket is provided with 20 a water intake opening 21 which is shown plugged, in Figs. 2, 4 and 5, but which obviously may be connected with any suitable water supply, and whereby the boiler may be filled and replenished from time to time with required 25 amounts of water.

22 represents an outlet in the top or dome portion of the heater, with which suitable hot water or steam supply pipes may be connected. A pipe 23 extends out from the upper rear portion of 30 the boiler, and is connected with the lower leg portions of the boiler by pipes 24—24, whereby a return circulation from the upper to the lower portion of the outer water jacket is insured.

35 The removable water container 15 is preferably cylindrical in shape, and as suggested, forms a cylindrical water container that is connected both front and rear with the outer water jacket in a way to insure a circulation of water to the best advantage to and from the outer water 40 jacket, and whereby the two said water containers will function as a single unit. With this object in view, I have provided a pipe extension 25 from the lower portion of the rear end of the removable water container 16, having a clean-out 45 plug 26 therein, and a somewhat similar pipe extension 27 from the lower front side of the removable container, which is also provided with a clean-out plug 28. The rear extension 25 of the removable water container and the extension 23 50 in the upper portion of the outer water jacket are provided with aligned pipes 29 and 30 that are connected by a union 31, see Figs. 2, 4 and 6, to form a circulating pipe connection between the upper portion of the outer water jacket and the lower portion of the removable water container.

60 A relatively short pipe 33 is extended forward from the upper portion of the removable cylindrical water container, and like the lower pipe 27 is provided with pipe connections 34—34 with the upper portion of the outer water jacket, so as to insure a proper circulation of water as between the outer water jacket and the inner water container. The pipes 32 and 34 are connected 65 with the outer water jacket by means of union elbows 35 whereby the pipes may be readily disconnected, should occasion require, as for the purpose of removing the inner cylindrical water container.

70 The front wall of the outer water jacket is provided on each side and on top of the inner water container with a clean-out opening 36, see Fig. 1, there being an elongated plate 37 secured to the inner crown sheet of the outer water jacket 75 that extends from the inner face of the front

wall of the water jacket adjacent the opening, to the inner face of the back wall of the outer water jacket, and is of a width to close the space between said crown sheet and the inner removable water container, to form a closed compartment that is accessible only through the said clean-out opening 36. The closing of this space on each side of the inner container is to insure the passage of the heat through the several heat 80 passages of the cylindrical water container. These openings 36, along with the cylindrical openings in the ends of the outer water jacket, are closed by plates 38, 39 and gaskets 40, which are secured to the outer face of the front portion of the outer water jacket by means of screw bolts, as shown. 85

41 and 42 represent baffle plates secured to the underside of the right and left portions of the crown sheet, see Figs. 1 and 2, that extend from the rear, forward, in spaced relation to the front end so as to form heat passages 43, and so that as the heat passes out through the opposite outlet openings of the water container, it is directed first forward along the underside of the baffle plate 41, then through the opening 43 to the central opening 44 which communicates with the smoke outlet 14. 90

95 The removable water container 15 is formed of an outer cylindrical shell and inner walls which together with the front and rear end members 45 and 46 form an elongated cylindrical water container, and a pair of elongated heat passages 47 and 48 both of which are oval in cross section. The lower passage 47 is provided in its rear end portion with inlets 49 that permit the 100 heat from the combustion chamber to enter and pass forward. The forward end portions of these two passages 47 and 48 are connected by a vertical passage 50 that serves to allow the heat which travels forward through the lower passage 47 to 110 pass up into the upper passage and return rearward to the outlets 51 which preferably extend out in opposite directions, and whereby the heat is caused to travel twice through the length of the removable container, in addition to the other 115 longitudinal passages provided between the inner and outer water containers. 120

125 A perforated baffle plate 52 is secured in the in the forward end of the heat passages 47, 48 and 50, see Figs. 1 and 4, in spaced relation to the closure plate 38—39 by means of screws set in holes of the baffle plate and threadably engaging lugs 53 projected inward from the inner wall of the removable water container. The rear end of 130 these passages 47 and 48 are also provided with somewhat similar though smaller perforated baffle plates 54 which are also positioned in spaced relation to the rear closure plate 38—39 and secured in position in a similar manner to that of the front baffle plate 52 by means of screws passing therethrough and engaging lugs 55 projected inward from the inner walls of the removable water container, these baffle plates being positioned in spaced relation to the closure plates and being perforated, obviously serve to protect the 140 closure plates against the heat which travels forward and backward through these passages. 145

Having thus described my invention, what I claim and desire to secure by Letters Patent is:

1. A boiler of the class described including a 145 combustion chamber and aligned cylindrical openings in its opposite ends, an inner removable cylindrical water container positioned in the boiler and loosely supported in the cylindrical openings and having a lower and an upper elongated 150

ELMER A. HOOPER.
